INVENTOR

Richard Hobbs.

UNITED STATES PATENT OFFICE.

RICHARD HOBBS, OF SAN DIEGO, CALIFORNIA.

LATHING-HATCHET.

1,199,984.

Specification of Letters Patent.

Patented Oct. 3, 1916.

Application filed July 3, 1915. Serial No. 88,915.

To all whom it may concern:

Be it known that I, RICHARD HOBBS, a citizen of the United States, residing at San Diego, in the county of San Diego and State 5 of California, have invented certain new and useful Improvements in Lathing-Hatchets, of which the following is a specification.

My invention relates to indicator devices 10 to be used in connection with lathing hatchets and other like tools or implements, and the objects of my invention are: First, to provide an indicator device of this class which will facilitate the keeping of account 15 of the amount of work done by the tool user, for instance the number of laths put on by a lather; second, to provide a device of this class which is applicable to a large variety of tools, and third, to provide a device of 20 this class which is simple and economical of construction, durable, easily constructed, and will not readily get out of order or arrangement.

With these and other objects in view as 25 will appear hereinafter my invention consists of certain novel features of construction, combination and arrangement of parts as will be hereinafter described in detail and particularly set forth in the appended 30 claims, reference being had to the accompanying drawings and to the characters of reference thereon which form a part of this specification, in which:

Figure 1 is a perspective view of an ordinary lathing hatchet with my indicator device connected therewith. Fig. 2 is a perspective view of one of the spring clamps used in connection with the hatchet handle. Fig. 3 is a sectional view through the 40 handle 1 on the line A—B of Fig. 1. Fig. 4 is a view of the hatchet with the head up showing the index numerals from 0 to 100, and Fig. 5 is a similar view of the hatchet with the blade up showing the index numerals from 0 to 10.

Similar characters of reference refer to similar parts throughout the several views.

The handle 1 is provided with a plurality of pairs of longitudinal V shaped grooves 50 1^a preferably in the small part of said handle near the hatchet and in one side of each of said grooves and communicating therewith are a plurality of notches 1^b, and on said handle between the separate members 55 of each pair of grooves 1^a is a row of

numerals. In this case I have shown two, 1^c and 1^d, the one 1^c numbering from 0 to 100 and the other 1^d numbering from 0 to 10. Mounted over a portion of the handle and adapted to rest in a pair of the grooves 1^a is the spring clamp 3 which is provided with inwardly extending V shaped ribs 3^a which fit into said grooves 1^a, and the metal is bent back against the other member as shown at 3^b. The ribs 3^a are connected together by a 60 pair of spaced apart straps 3^d which extend around a portion of the handle and upon which are mounted adjacent the ribs 3^a the lugs 3^c which are adapted to fit in the notches 1^b in the handle for holding the 70 spring clamp 3 in position on the handle and prevent the moving of said clamp on said handle by jar in using the hatchet. The numerals in the index rows 1^c and 1^d are so spaced that when the lugs 3^c are positioned 75 in the notches 1^b said numerals will be between the two bands 3^d. It will be here noted that the spring clamp 3 is to be moved along the handle in the grooves 1^a and notches 1^b as the lather finishes a bundle of 80 lath, thus providing an indicator on the hatchet handle for keeping account of the number of laths put on.

Though I have shown and described a particular construction, combination and arrangement of parts in connection with a lathing hatchet, I do not wish to be limited to this particular construction, combination and arrangement, but desire to include in the purview of my invention the construction, combination and arrangement substantially as set forth in the appended claims.

It is obvious that with this construction there is provided indicator means to be used in connection with lathing hatchets and the like for indicating the number of laths put on by the lather; that by the use of the two spring clamps and two sets of numerals any number of bundles of lath may be readily kept, for instance, if it is desired to register 100 eighteen bundles, the spring clamp 3 would be moved on the handle over the numerals 1^c to the numeral 10 and the other spring clamp over the numerals 1^d to the numeral 8, and so on as desired; that the device is 105 simple, economical of construction, durable, easy to operate and will not readily get out of order; and that it is applicable to a large variety of tools and the different makes of lathing hatchets now in use.

Having thus described my invention what I claim as new and desire to secure by Letters Patent, is:

1. In a device of the class described, the combination of a tool handle provided with a pair of longitudinal grooves therein and with a row of numerals between said grooves and a spring clamp adapted to fit in said grooves and over said row of numerals 10 adapted to be moved manually along said handle in said grooves.

2. In a device of the class described, the combination of a tool handle provided with a pair of grooves spaced apart longitudinally in said handle, a series of notches 15

spaced a certain distance apart communicating with said grooves, a row of numerals interposed between said grooves, and a spring clamp mounted on said handle over said row of numerals provided with inwardly extending ridges adapted to fit in said grooves and with lugs adapted to engage said notches, whereby said spring clamp will be held in certain position on said handle but may be moved manually thereon.

RICHARD HOBBS.
